US00D889978S

(12) **United States Design Patent** (10) **Patent No.:** **US D889,978 S**
(45) **Date of Patent:** **** Jul. 14, 2020**

(54) **CAN PANEL**

(71) Applicant: **Ardagh MP Group Netherlands B.V.**,
Deventer (NL)

(72) Inventor: **Fabrice Leboucher**, Crosmieres (FR)

(73) Assignee: **Ardagh MP Group Netherlands B.V.**,
Deventer (NL)

(**) Term: **15 Years**

(21) Appl. No.: **29/661,382**

(22) Filed: **Aug. 27, 2018**

(30) **Foreign Application Priority Data**

Jun. 14, 2018 (EM) 005310802

(51) **LOC (12) Cl.** **09-01**

(52) **U.S. Cl.**

(57) **CLAIM**

The ornamental design for a can panel, as shown and described.

DESCRIPTION

FIG. 1 is top perspective view of a can panel showing the new design;

FIG. 2 is a bottom perspective view of the can panel design;

FIG. 3 is a top plan view of the can panel design;

FIG. 4 is a bottom plan view of the can panel design; and,

FIG. 5 is a top perspective view, partially broken away for clarity, of the can panel design.

In the drawings, the broken lines showing portions of a can depict environment for the can panel and form no part of the claim.

1 Claim, 5 Drawing Sheets
